232,881

CHAIR

Stapleton Long, 1629 Christmas Drive,
Morristown, Tenn. 37814

Filed Feb. 20, 1973, Ser. No. 334,147

Term of patent 3½ years

Int. Cl. D6—01

U.S. Cl. D6—37

FIG. 1.

FIG. 2.

FIG. 1 is a front perspective view of a chair showing my new design; and

FIG. 2 is a left side perspective view, the right side being a mirror image thereof.

The chair back is plain and conventional throughout.

I claim:

The ornamental design for a chair, as shown and described.
